LAMINATED WALL STRUCTURE

William C. Scherer, Detroit, Mich.

Application August 5, 1933, Serial No. 683,784

5 Claims. (Cl. 189—34)

My invention relates to improvements in wall structures for buildings.

One object of this invention is to provide an economically constructed wall structure possessing the inherent quality of supporting loads throughout the length of the wall structure.

Another object is to provide a wall structure for a building which can be constructed in separate units and assembled quickly and easily on the building site.

A further object is to provide a firm, durable wall structure which possesses the inherent ability of distributing stresses imposed upon one portion thereof to adjacent portions and which also possesses an inherent resiliency permitting the wall to sustain pressure directed normally thereto without permanent deformation.

Another object of my invention is to provide in a wall structure a corrugated, reversely curved, or otherwise similarly formed metal sheet of such a formation that it readily transfers the stress imposed on any portion to adjoining portions. The metal sheet is so shaped that, in the formation thereof, the metal in the sheet is worked or stressed approximately equally throughout its entire area, and the metal as a result is substantially constant and uniform in character throughout every part of the sheet.

A further object is to provide a wall structure with an insulation section which not only reduced the heat conductivity through the wall but also strengthens the wall structure and cushions impacts imposed upon the wall.

An additional meritorious characteristic is that my laminated wall structure has its several laminations so secured together and particularly the laminations which are secured to the corrugated metal sheet are so fastened to the crests thereof as to permit flexibility and resiliency of the lamination of the structure to meet required demands and permit relative movement.

A still further object is to provide a wall structure for a building which has little heat conductivity, considerable sound absorbing characteristics, and is inexpensive to make.

Further objects and meritorious features of my invention will become apparent from the following description and accompanying drawing wherein like numerals refer to like parts throughout the several figures and wherein:

Figure 1 is a perspective of the wall structure, broken away for the purpose of clearness,

Figure 2 is a sectional view of a plurality of wall units and the manner of joining them together,

Figure 3 is a sectional view of a modification illustrating a slightly different manner of assembling the wall structure,

Figure 4 is a sectional view of one formation of the corrugated metal sheet,

Figure 5 is a sectional view of another formation of the corrugated metal sheet, and

Figure 6 is a sectional view of another formation of the corrugated metal sheet.

The wall structure is a laminated construction having a corrugated metal sheet forming one of the laminations. As illustrated in the drawing, particularly Figure 1, a metal sheet 10 has vertical corrugations rolled therein. These corrugations are made up of a continuous succession of alternate reversely curved portions throughout the extent of the metal sheet.

On one side of the corrugated sheet 10 there may be mounted a fiber board 12 or any other suitable panel or sheet material for forming the wall surface of a room in a building. In order to secure this panel to the corrugated metal it is preferred that a yieldable, non-hardening adhesive be spread over the crests of the corrugations as indicated at 14. This panel may also be secured by means of rivets or stitches. A strip of felt or similar material may be used in place of the adhesive in this case. This is to take up variations occurring in fabrication and also to dampen forces being transmitted through the wall structure from layer to layer.

On the side of the corrugated sheet metal opposite to the panel 12 there is mounted a panel of fiber boards 16 which may be corrugated. This panel in the embodiment disclosed herein consists of a series of corrugated and flat fibre boards permanently held together and forming a heat insulation for the wall structure. To permanently but yieldably position this insulation against the corrugated sheet metal non-hardening adhesive 14 or other securing means may be used as previously mentioned. In place of the fiber boards 16 a panel of homogeneous fibrous material or any other substance having insulative qualities may be used. Between the corrugated sections and the panels on either side a plurality of dead air pockets 18 are formed which aid considerably in preventing the transmission of heat and sound through the wall structure.

To form an outside protective coating for the wall structure, a flat sheet of metal 20 may be secured to the insulation 16 by the adhesive 22. In place of the metal sheeting, paper or any other suitable protective material may be utilized.

In Figure 2 there is illustrated a manner of

constructing the wall structure in separate units which are later assembled together to form the wall. The laminated construction of the wall is very similar to that in Figure 1. The corrugated metal sheets are cut in separate sections at certain spaced intervals. The edges of these sections may be turned in forming hook like fasteners as indicated at 24. Likewise, the insulation panel 16 is cut into sections equaling in length the corrugated metal sections. These cut off portions are indicated at 26. The sheet metal 20 is formed in slightly larger sections and the overlapping edges 28 are bent inwardly to secure the insulation therebetween. As previously described, suitable yieldable securing means may be used for securing the various parts together into a unitary structure.

After these wall units have been manufactured they may be shipped in separate units to the building site and there assembled together and erected into a wall structure for the building. In the erection of a wall composed of a plurality of wall units such as described, a fastening device comprising a split tube 32 may be used which is 25 slideable behind the fasteners 24 and secures the adjoining wall units together. A similar provision for joining two wall units is provided for the corners. Packing or caulking 30 is provided between the flanges 28 and the fasteners 24 in order 30 to weatherproof the cracks between the wall units and to lessen the heat conductivity through the wall by preventing metal-to-metal contact.

In Figure 3 a slightly different arrangement for assembling the wall structure together at the building site is illustrated. In this modification the corrugated metal strip is one continuous sheet and may be secured in vertical position before the addition of the insulation to the wall. As shown in Figure 2 the metal sheet 20 has at spaced intervals inwardly extending flanges 28 which in this particular case extend inwardly as far as the corrugated metal and may be spot welded thereto as at 34. Packing may or may not be provided between the flanges.

Figures 4, 5, and 6 illustrate various corrugated formations which may be used. The formation in Figures 4 and 5 are adapted to support heavy loads while that in Figure 6 is adapted for the support of lighter loads. In the various figures 45 illustrated in the drawing, with the exception of Figure 5, every portion of the convolutions making up the corrugated sheet metal is arcuate. In Figure 5, however, the mid-part of the convolution forms a straight section and the rest or 50 greater portion of the convolution is in curved section.

The wall structure is load supporting in itself. Every two adjacent corrugations in the metal sheet form a laterally displaced hollow column 60 for supporting the building. There is no need for providing additional vertical supports at the corners or intermediate portions of the building.

When loads are supported by the corrugated metal sheet stresses occur, and the arcuate formation of each portion of the corrugations readily transmit the stresses to adjacent portions of the metal sheet. The absence of sharp angle bends in the corrugated metal enable strains imposed on the wall structure to be spread over the 65 areas adjacent. The nearly constant physical characteristics of the formed section are contributing factors in this connection. Pressures and sudden shocks brought to bear against the

wall normal to the plane of the corrugated metal are yieldably received by the wall and transmitted through the flexibly curved portions of the corrugations.

The wall structure furnishes a strong, durable 5 construction which is at the same time somewhat flexible when certain abnormal strains and stresses are imposed thereon. The pliable, non-hardening adhesive or other yieldable means used to secure the laminations of the wall together 10 permits relative movement between the various parts of the wall structure when abnormal stresses are encountered. Although not limited to such application the wall structure is peculiarly adaptable to buildings in whose construction the 15 following features are of major importance; ease and speed of erection, high salvage value of materials, and ease of replacement in the case of units damaged during use or in the case of alterations.

Various other modifications of the structure illustrated will be apparent to those skilled in the art and for that reason I intend to limit myself only within the scope of the appended claims.

What I claim is:

1. A laminated wall structure comprising, in combination, a metal sheet having formed therein a continuous succession of reversely arranged corrugations, and sheet material secured to the crests of said corrugations on one side of said 30 metal sheet by lines of non-hardening pliable adhesive extending linearly along said crests.

2. A laminated wall structure comprising, in combination, a corrugated metal sheet, a flat metal sheet having marginal flanges arranged 35 adjacent to the corrugated metal sheet with the flanges abutting the crests of the corrugations, a sheet of insulation material arranged between the flat sheet and the corrugated sheet and enclosed by the flanges of the flat sheet and supported upon the crests of the corrugated sheet filling the space between the flat metal sheet and the crests of the corrugations of the corrugated metal sheet.

3. A wall structure for a building comprising, 45 in combination, a metal sheet shaped to provide a continuous succession of alternately curved convolutions, sheet material secured to the crests of such convolutions and a layer of cushioning material extending linearly along the crest of 50 each convolution between said sheet material and the metal sheet.

4. A laminated wall structure comprising, in combination, a corrugated metal sheet, a composite panel consisting of a metal sheet provided 55 with a backing of a sheet of insulation material secured thereto, said composite sheets overlying the corrugated metal sheet and secured to the crests of the corrugations with the insulation material arranged adjacent to the corrugated sheet.

5. A laminated wall structure comprising, in combination, a corrugated metal sheet, a layer of composite material consisting of a flat metal sheet having marginal flanges and a sheet of 65 insulation material arranged adjacent to said flat metal sheet and enclosed by the marginal flanges thereof with the insulation material lying adjacent thereto and held to the metal sheet thereby, said layer of composite material secured to the crests of the corrugations of the corrugated metal sheet with the insulation material lying adjacent thereto.

WILLIAM C. SCHIERER.
